(57) **CLAIM**

The ornamental design for a musical toy, as shown and described.

DESCRIPTION

FIG. 1 is a top perspective view of a musical toy, showing the new design.

FIG. 2 is a bottom perspective view of the musical toy of FIG. 1.

FIG. 3 is a front elevational view of the musical toy of FIG. 1.

FIG. 4 is a back elevational view of the musical toy of FIG. 1.

FIG. 5 is a left elevational view of the musical toy of FIG. 1.

FIG. 6 is a right elevational view of the musical toy of FIG. 1.

FIG. 7 is a top plan view of the musical toy of FIG. 1; and, FIG. 8 is a bottom plan view of the musical toy of FIG. 1. The broken lines in the drawings depict portions of the musical toy that form no part of the claimed design.
